(57) **CLAIM**

The ornamental design for a wheel module for personal mobility, as shown and described.

DESCRIPTION

FIG. 1 is a top, front and right-side perspective view of a wheel module for personal mobility according to the present invention;

FIG. 2 is a front elevation view thereof;

FIG. 3 is a rear elevation view thereof;

FIG. 4 is a left-side view thereof;

FIG. 5 is a right-side elevation view thereof;

FIG. 6 is a top plan view thereof; and,

FIG. 7 is bottom plan view thereof.

1 Claim, 7 Drawing Sheets
